GEORGE M. HARSH, AND NOAH DILLENBURG, A PARTNERSHIP KNOWN AS E.
ROSENFIELD & CO., OF BALTIMORE, MARYLAND.

METHOD OF MAKING NECKBANDS.

1,031,011.

Specification of Letters Patent.

Patented July 2, 1912.

Application filed October 25, 1911. Serial No. 656,686.

To all whom it may concern:

Be it known that I, ALBERT LION, a citizen of the United States of America, residing at the city of Baltimore, State of Maryland, have invented certain new and useful Improvements in Methods of Making Neckbands, of which the following is a specification.

This invention relates to a neck band having a front or end pocket for the back or base of the collar button and particularly to a method of producing the same.

The object of the invention is to provide such a neck-band having a pocket to protect the neck from the base of the collar button, the neck band to be easy of production and durable, the pocket being preferably open top and bottom and so designed as to offer great resistance to tearing or ripping when opened as for the purpose of inserting the stud after the shirt has been laundered. To this end I make the lining or walls of the pocket of a single piece of material. The seam is preferably located at the end of the band and is identical with the seam which joins the ends of the strips of which the band is composed. It will be apparent that when the pocket is opened up, a continuous lining will offer greater resistance to enlargement of the pocket by ripping than would a pocket made with a seam at each end.

In the production of my improved neck band by the preferred method, the top edge of the lining strip is sewed for one half its length to the top edge of the neck strip proper at one end. Then the other half of the top edge of the lining strip is sewed to a corresponding portion of the top edges of the reinforcing neck strips. Next the lining is reversed and its bottom edge is sewed to the bottom edge of the first neck strip, the edges being turned in. The parts are then folded so that the reinforcing strips are on one side of the neck strip and the half of the lining, which has been sewed at its top edge to the top edge of the reinforcing strips, is on the other side of the lined end of the first neck strip. The top edges of the neck strips are then sewed together, the seam thus formed avoiding the top edge of the lined end of the first neck strip. Then the seam is deflected downward so that the end edges of all the strips are stitched together.

Next the band thus formed is turned inside out so that the first neck strip is on the one side and the reinforcing neck strips are on the other side, the lining being between.

A shirt band constructed in accordance with my method and embodying the features of my invention is illustrated in the accompanying drawings.

Figure 1 shows the lining sewed at its top edge to the top edge of the neck strip proper. Fig. 2 shows the neck strip proper and the reinforcing neck strips with the lining, the top edges of the latter being sewed to the corresponding portions of the top edges of the neck strips, the lining being also shown in dotted lines in a subsequent position. Fig. 3 shows the neck band after the top edges of the strips and the end edges have been seamed. Fig. 4 shows the completed neck-band.

The neck-band of my invention consists of a neck strip proper 1, a pocket lining 2, and two reinforcing neck strips 3 and 4. The pocket, in its preferred embodiment, is formed in the end of the neck-band and is open top and bottom. It is between the neck strip proper 1 and the inner member 3 of the reinforcing neck strips. The lining or walls proper of the pocket are formed entirely of the lining piece 2 which is folded upon itself between the strips, as I have related, the two end edges 5 and 6 of the lining piece 2 being engaged by the end seam 10 which joins the end edges of the neck strips 1, 3 and 4. The end of the neck strip proper 1 is reinforced by the half of the lining 2. In this the buttonhole 11 is worked. The lined end of the neck strip, as thus constructed, is narrower than the neck-band, its lower edge being above the bottom edge of the neck-band so that the pocket is easy of access from without.

In the practice of the preferred method of producing the neck strip, the top edge of one half of the lining member 2 is sewed to the top edge of the neck strip proper 1, and the top edges of the ends of the reinforcing strips 3 and 4 are sewed to the other half of the top edge of the lining member 2, the latter being folded upon itself between the neck strips. The article in the stage of production which we have just described is best illustrated in Fig. 2. Next the lining member 2 is turned inside out and brought to the

position shown by dotted lines X in the same figure, and one half of the bottom edge is inturned and sewed at 16 to the bottom edge of the neck strip proper 1 which is also in-turned. Then the parts are so placed that the reinforcing strips are on one side of the neck strip proper 1 and the portion 2' of the lining, the top edge of which has been sewed to the top edges of the reinforcing strips 10 3 and 4, is on the other side of the neck strip proper. In this position the top edges of the strips are sewed together, the seam 15 avoiding the top edge of the lined end of the neck strip proper. The seam is then deflected 15 downward to join the end edges of all the strips. Next the neck strip proper 1 is folded away from the reinforcing neck strips 3 and 4 and the band is virtually turned inside out. Then the seam 12 is passed along 20 the top edge of the neck-band below the seam which we have just described. The buttonhole 11 is worked at any convenient point in the process, and the collar may be permanently attached or buttoned.

25 In the production of the neck-band, it is within the scope of my invention to first sew one half the top and bottom edges of the lining strip 2 to the corresponding top and bottom edges of the end of the neck strip 1, 30 see dotted lines in Fig. 1, then turn the tube thus formed inside out, and if desired, to seam the top and bottom edges as at 13 and 14. Then the operation may be continued by sewing the top edge of the other half of 35 the lining member 2 to the top edges of the reinforcing neck strips 3 and 4, and proceeding as before.

It will be apparent that the cost of my neck-band produced by either of the methods 40 which I have described, will not be greatly in excess of that of the ordinary neck-band without the pocket, and that the pocket so constructed is not subject to the usual defects of collar button pockets in that it is 45 not easily ripped in opening and is also easily opened.

I have thus described in minute detail a single embodiment of the article of my invention, and have also described two 50 methods by which it may be produced, and have emphasized various details in order that the article which I produce may be clearly understood. However, the specific terms herein are used in their descriptive 55 rather than in their limiting sense, and the scope of the invention is defined in the claims.

I claim—

1. A method of making a neck-band end pocket which consists in sewing one half of 60 the top edge of a lining member to the top edge of the neck strip proper near one end, sewing the top edge of a reinforcing neck strip to the other half of the same edge of the lining member, turning the lining member 65 inside out, *i. e.*, upward about its top edge, and sewing the bottom edge of the first named half of the lining member to the corresponding bottom edge of the neck strip proper, bringing all the strips into 70 registration, so that the lined end of the neck strip proper is between the reinforcing neck strip and the free portion of the lining, *i. e.*, that part, the top edge of which is sewed to the reinforcing neck strip, sewing the top 75 edges of the neck strips together avoiding the lined portion of the neck strip proper, sewing the end edges together, including the edges of the lining member, then turning the neck-band thus formed inside out, 80 *i. e.*, folding over the neck strips so that they come one on each side of the band with the neck strip proper externally placed.

2. A process of making a neck-band end pocket for the stud base which consists in 85 sewing half the top and bottom edges of a lining member to the top and bottom edges of a neck strip proper, and sewing the top edges of reinforcing neck strips adjacent their ends to the other half of the top edge 90 of the lining member, bringing all the strips into registration so that the lined end of the neck strip proper is between the reinforcing neck strips and the free portion of the lining, *i. e.*, that part, the top edge of which 9 is sewed to the reinforcing neck strips, sewing the top edges of all the neck strips together avoiding the top edge of the lined end of the neck strip proper, sewing the end edges of all the neck strips, including the 100 lining member, together, then swinging the neck strip proper about its top edge away from the reinforcing neck strips, and rotating it through a complete circular arc so that the surfaces of the strips which were previously turned outward are now inward, *i. e.*, turning the band inside out, and next sewing the top edges of the strips to hold them in this position.

Signed this 23d day of October, 1911.

ALBERT LION.
